EDWARD SNYDER, OF SLATINGTON, PENNSYLVANIA, ASSIGNOR TO HIMSELF AND MORGAN JONES, OF SAME PLACE.

Letters Patent No. 76,951, dated April 21, 1868.

IMPROVEMENT IN MACHINES FOR ROUNDING THE CORNERS OF SLATE-FRAMES.

The Schedule referred to in these Letters Patent and making part of the same.

TO ALL WHOM IT MAY CONCERN:

Be it known that I, EDWARD SNYDER, of Slatington, in the county of Lehigh, and State of Pennsylvania, have invented certain new and useful Improvements in Machines for Rounding the Corners of Slate-Frames and analogous articles; and I do hereby declare that the following is a full and exact description thereof.

My machine operates by means of a rapidly-revolving cutter, or wheel provided with cutting-teeth, mounted in fixed bearings. The slate, or other article to be rounded, is first made with right-angled corners, as usual, and each is successively introduced in a slide, with a corner presented towards the cutter-wheel, and is moved past the cutting-wheel. The frame is guided in a curve, so that the slate is caused to recede from and to approach the cutting-wheel as it is moved past, and thus producing exactly the curve required. A spring is introduced, to throw the slide back to its original position as soon as a corner is finished, and the slide may be turned in the frame, so as to present a new corner, and thus repeat the operation very rapidly.

I will proceed to describe in detail what I consider the best means of carrying out my invention.

The accompanying drawings form a part of this specification.

Figure 1 is a front view,

Figure 2 is a plan view, and

Figure 3 is an end view of the entire machine.

Figure 4 represents the cutter and shaft on a larger scale.

Similar letters of reference indicate like parts in all the figures.

A is a rigid framework; B is an upright shaft, mounted therein, driven by a belt from a steam-engine or other convenient power, not represented; and C is a cutter-wheel, which may be formed in any approved manner, and provided with sharp cutters, adapted to remove the wood presented thereto.

D is a slide, which may be formed of a piece of hard board or light plank, supported on the sides of the frame, as represented, and provided with two gauges, D¹ D², on the upper face. These gauges stand at right angles to each other, and are adapted to receive a slate of any size, and to present the corner between the gauges to be acted on by the cutter.

The edge of the slide D is hollowed out each side of the point where the corner of the slate is held, as indicated by d³ d⁴. This allows the slide to be moved up very closely to the cutter-wheel at this point.

a¹ a² are pins, fixed in the top of the frame where the slide D is supported; and these pins are received in curved slots d¹ d². The pieces A¹ A², fixed on the framing A, stand in contact with the upper face of the slide D, and confine it against becoming displaced. The cutter-wheel C acts on the other side of the machine, through a hole in the upright guide A³, to trim and properly finish the straight edges of the slate-frame or other article to be treated. This portion of the mechanism is common to other machines operated for this purpose, and need not be particularly described.

The operation of my machine will be readily understood. The cutter-wheel C being set in motion at a high velocity, the slates, with their frames, are laid successively on the slide D, with the two edges against the gauges D¹ D², and the slide is moved to the right by the force of the hand applied in an obvious manner. In effecting this movement, the slide, being guided by the pins a¹ a², standing in the curved slots d¹ d², during the early portion of the movement, recedes from the cutting-wheel C, and, during the latter portion of the movement, approaches toward the cutter-wheel C. The curvature of the slots d¹ d² is so proportioned to the size of the wheel C as to produce, by this motion, exactly the curvature required. The movement of the corner of the slate in this manner past the cutter presents it in such a manner as to just remove a sufficient quantity of the material, and in a right position to round the corner perfectly. As soon as this movement is completed, the slide D, with its connections, returns to its original place by the action of the spring E, mounted underneath, as represented. The slate is now drawn back on the slide D, and is turned one quarter around, and thrust back into contact with the gauges D¹ D², and again the slide D, with its connections, is moved to the right, as before.

This operation is repeated, turning the slate over, as well as around, when necessary, in order to present the grain of the wood in the most advantageous manner to the action of the cutter. My machine, by holding the slate in a fixed position upon the slide D, and moving it past the cutter in this manner, allows the cutters to act with more advantage, and with less liability to split or roughen the corners, than any other machine for the purpose known to me.

I prefer, in practice, to make the gauge D² overhang a little, so as to press slightly on the upper edge of the slate-frame, and hold it firmly down upon the slide D while under the action of the cutters. What I esteem the preferable mode of constructing this is indicated in the drawings, there being a piece of sheet steel or other suitable material screwed down upon the slide D, and bent over, to form the gauge.

Having now fully described my invention, what I claim as new in machines for rounding the corners of slates and analogous articles, and desire to secure by Letters Patent, is as follows:

I claim the curved guides d¹ d² and pins a¹ a², or their equivalent, arranged and operating, relatively to the cutter C and carrier D, substantially as and for the purposes herein set forth.

EDWARD SNYDER.
